ELMER E. BUTCHER, OF INTERLAKEN, NEW JERSEY, ASSIGNOR TO MARCONI WIRELESS TELEGRAPH COMPANY OF AMERICA, A CORPORATION OF NEW JERSEY.

METHOD OF AND APPARATUS FOR ELIMINATING STATIC EFFECTS.

1,306,170.

Specification of Letters Patent. Patented June 10, 1919.

Application filed July 20, 1915. Serial No. 40,820.

To all whom it may concern:

Be it known that I, ELMER E. BUTCHER, a citizen of the United States, residing at Interlaken, in the county of Monmouth, 5 State of New Jersey, have made certain new and useful Improvements in Methods of and Apparatus for Eliminating Static Effects in Radio Receiving Apparatus, of which the following is a specification.

10 This invention relates to a method of and apparatus for eliminating static effects in radio signal receiving apparatus. The object of the invention is to render radio signaling continuously practicable. The invention comprises the use of an antenna circuit containing adjustable inductance and capacity; two local oscillating circuits each containing adjustable means for causing said circuits to generate or exhibit high frequency oscillations, means for associating said circuits with a third circuit containing adjustable inductance and capacity; and a receiving device, like a receiving telephone; adjusting or tuning said two local circuits 25 to frequencies above audibility and respectively different, and said third circuit to a frequency lower than that characteristic of either the antenna circuit or the two local circuits referred to and within the range of 30 audibility.

By "static" it is intended to include any atmospheric disturbance of the electro-equilibrium, such as that due to lightning discharges, near or remote, or charged particles 35 in the atmosphere which may set up disturbing influences in the receiving apparatus.

There is provided an antenna containing adjustable inductance and capacity and two local oscillating circuits of substantially 40 identical arrangement; each of these circuits contains an oscillation generator, like the well-known vacuum valve adjusted to generate high frequency, sustained oscillations, above audibility; these two circuits are so 45 adjusted as to avoid establishing by their characteristic frequency a conjoint note, that is, any note due to their coupled cooperation upon a third circuit coupled with said two local circuits. This third local circuit 50 includes means for tuning and is tuned to a lower frequency than that characteristic of either of said first named local circuits, and preferably to a frequency suitable to the

best operating characteristic of the receiving telephone employed.

In the drawings the antenna circuit includes the elevated wire, 1, variable tuning inductance, 2, variometer inductance, 3, primary winding of the oscillation transformer, 4, variable condenser 5 shunting the coil 4, 60 the second primary winding 6, connected in series with primary winding 4, the variable condenser 7 in shunt to winding 6 and earth connection 8. There are two local oscillating circuits, *a* and *b*, which are substantially 65 identical. Circuit *a* contains secondary winding of oscillation transformer 9, placed in inductive relation to the primary winding 4. There is a secondary loading coil 10 and variable condenser 11 connected in shunt to 70 inductances 9 and 10. This local circuit also includes the variable condenser 12, connected in series with the grid of the vacuum valve 13, one terminal being connected to the high potential terminal of coil 10. 75 Variable condenser 14 is connected in series with inductance coil 15, both being shunted across the high potential, direct current generator 16 and the primary winding of the audibility circuit transformer 17. 80 The primary winding 17 is placed in inductive relation to the secondary winding 18. The vacuum valve includes a grid 13, a cold element 19 and a hot element 20; the heating battery and controlling resistance are 85 shown at 21 and 22, respectively. Coil 15 is placed in adjustable inductive relation to coil 10.

The local oscillatory circuit, *b*, contains the variable secondary winding 23; the variable loading coil 24 and the variable condenser 25, connected in shunt to winding 23 and coil 24. The condenser 26 is connected in series with the grid 27, one terminal of which is connected to the high potential terminal of coil 24. The variable condenser 28 is connected in series with the coil 29, both being shunted across the direct current generator 30 and the primary winding of the audibility circuit transformer 31. The vacuum 100 valve contains cold plate 32, hot element 33 and grid element 27, the heating battery 34 and its current varying resistance 35. Circuits *a* and *b* are connected to earth at 36 and 37, as shown. The primary winding 105 of the audibility circuit transformer, 31, is

placed in inductive relation to the secondary winding 38. The telephone receiving circuit or audibility circuit, *c*, contains the windings 18 and 38 and the variable condenser 39, all connected in series. The telephones, 40, are connected in shunt to the variable condenser 39.

The method of operation is as follows: The filament 20 of circuit *a* is brought to a certain degree of incandescence and a certain value of potential selected at the battery 16, followed by the adjustment of condenser 14 until inductance 15 and condenser 14 have, flowing through them, undamped oscillation. The frequency of these oscillations will depend upon the value of capacity selected at the condenser 14. Similar effects are produced by alteration of the value of inductance in use at coil 15. These oscillations are increased in amplitude by placing coil 15 in inductive relation to coil 10, followed by a variation of the capacity of condenser 11, or, if desired, by variation of inductance at coils 9 and 10 until the circuit comprising the elements 9, 10 and 11, is in resonance with the circuit having the elements 14 and 15. The oscillations flowing in 9, 10 and 11 charge the grid condenser 12 which leaks off to the grid 13, causing corresponding reduction in the current flowing between the hot element 20 and the cold plate 19; both on account of the "trigger" action of the valve and the reaction of coil 15 on coil 10 undamped oscillations of increased amplitude are thus maintained in both circuits. The elements 9, 10, 11, 12, 13 and earth connection 36 constitute the grid circuit. The elements 14, 15, 16, 17, 19 and 20 constitute the wing circuit. It is preferred, in practice, that the adjustments for frequency in the grid and wing circuits be made at the condensers 11 and 14, condenser 12 generally remaining at a fixed small capacity value. Similar adjustments are made throughout in the local circuit *b*. In adjusting to receive signals from a distant station, the variable elements of the antenna circuit are adjusted for resonance with the incoming wave. The variable elements of circuit *a* are adjusted to a frequency sufficiently different from that of the antenna circuit to produce "beats" in the grid circuit, above the limits of practical audibility. Similar adjustments are made at the local oscillatory circuit *b*, but this circuit has a frequency differing from that of circuit *a*. Such adjustments are made in circuit *b* as to produce "beats" also above the practical limits of audibility but differing in frequency from those "beats" in circuit *a* by a certain predetermined rate. The "beats" produced in both circuits *a* and *b* are amplified by the well-known trigger action of the vacuum valve and these "beats" cause corresponding variation of current through

the coils 17 and 31. A change of lines of force takes place in the coils 17 and 31 which cause corresponding alternating current to be set up in the secondary windings 18 and 38, and also the condenser 39. If the currents in coils 18 and 38 were identical in frequency and amplitude no sound would be produced in the telephones 40, but if the frequencies in secondary coils 18 and 38 differ by a predetermined amount audible "beats" suitable to the head telephones 40 will be produced. The natural frequency of the telephone circuit may be varied or altered either by variation of inductance of coils 18 and 38 or by alteration of the capacity or condenser 39.

Since static impulses picked up by the receiving aerial have no distinct time period of vibration, being very highly damped, pure beats are not produced but current pulses of about equal intensity are set up in the primary windings 17 and 31 and by suitable selection of the coupling between coils 17 and 18, also between coils 31 and 38 the resultant currents due to static impulses may be made equal and opposite and therefore completely neutralized.

I have discovered that the practical range of audibility for the average magneto receiving telephone is within four or five thousand cycles per second; and in some cases less. I have attained good results from tuning the antenna circuit to a frequency of 40,000 cycles; local circuit, *a*, to 45,000 cycles; local circuit, *b*, to 36,000 cycles; the interaction of the 45,000 cycle energy in circuit, *a*, upon the 40,000 cycle energy in the antenna circuit will produce in circuit, *a*, "beats" at a rate of 5000 cycles per second which, in turn, will cause 10,000 pulses of current per second in coil 17 of circuit *a*; similarly the 36,000 cycle energy in circuit, *b*, interacting upon the 40,000 cycle energy in the antenna circuit will cause a beat frequency of 4000 cycles per second in circuit, *b*; this, in turn, will cause 8000 pulses of current per second in primary winding 31 of circuit *b*. We thus have set up in coil, 18, a fundamental frequency from primary winding, 17, of 5000 cycles per second and in winding, 38, a fundamental frequency due to winding, 31, of 4000 cycles per second; the interaction of the frequencies in coils, 38, and, 18, will cause a beat phenomena in circuit, *c*, of 1000 cycles per second; I am aware that under certain degrees of saturation the coils, 17, and, 31, an alternating current of double frequency will flow in coils, 18, and, 38, but this will in no wise interfere with the above-described "beat" action; it only being then necessary to select a lower order of frequency in coils 17 and 31.

What I claim is:

1. The method of eliminating static, which consists in subjecting the received oscilla-

- tions and the static impulses to the effect of two interacting unlike locally generated high frequency oscillations, and then combining the resulting oscillations of the above interaction in such a manner as to entirely eliminate the resultant oscillations arising from the combination of the static impulses and the locally generated high frequency oscillations.
- 10 2. In a radio signal receiving station, two substantially identical interacting circuits, adapted to generate unlike high frequency oscillations, associated with an antenna circuit, the said generating circuits being inductively coupled to a third circuit comprising a receiving device, said third circuit being tuned to a frequency corresponding to the difference of the frequencies of the two interacting circuits.
- 15 3. In a radio signal receiving station the combination of an antenna circuit including variable inductance, a local circuit including an oscillation generator of high frequency, a second local circuit including an oscillating generator of high frequency, means for associating both said circuits with the antenna circuit; a third circuit containing tuning devices and a wave responsive device and means for associating said circuit with said local circuits.
- 20 4. In a radio signal receiving station the combination of an antenna circuit including a variable inductance, a local oscillating circuit including a generator of high frequency oscillations, a second local oscillating circuit including a generator of high frequency oscillations, means for associating both said circuits with the antenna circuit, a third local circuit containing a variable inductance and a variable capacity with a receiving telephone and means for associating said circuit with said local circuits.
- 25 5. In a radio signal receiving station the combination with the antenna circuit of two local circuits of substantially identical arrangement containing sources of energy and tuned to a predetermined frequency and associated with the antenna circuit, a third local circuit tuned to a comparatively low frequency and associated with said local circuits independently of said antenna circuit, a telephone receiver in said third circuit and means for causing the two local circuits and the antenna circuit to react on each other.
- 30 6. The combination in a radio signal receiving station with antenna of two local circuits containing sources of energy, means for causing said local circuits and said antenna to react on each other, a third local circuit, means for associating said third circuit with both first named local circuits, a receiving device in said third circuit and means for adjusting said third circuit to a lower frequency than that characteristic of the two local circuits.
7. The combination in a receiving station of an antenna circuit, two local circuits coupled to said antenna circuit, the coupling members in said antenna circuit being in series, sources of independent electrical impulses in said secondary circuits, and a third local circuit coupled to both the other local circuits independently of said antenna circuit.
- 75 8. The combination in a radio signal receiving station of an antenna circuit, two local circuits coupled to said antenna circuit, the portions of the couplings for said local circuits in said antenna circuit being in series, said local circuits having sources of independent electrical impulses therein and being tuned to frequencies one above and one below that of the antenna circuit, and a third local circuit coupled to both the local circuits independently of said antenna circuit.
- 80 9. The combination in a radio signal receiving station of an antenna circuit, two local circuits coupled to said antenna circuit and having sources of independent electrical impulses therein, the portions of the couplings for said secondary circuits in said antenna circuit being in series, and a third local circuit coupled to said other local circuits independently of said antenna circuit, each of said three local circuits containing independent means for varying the natural period thereof.
- 90 10. The combination in a radio signal receiving station of an antenna circuit, two local circuits coupled to said antenna circuit and containing independent sources of electrical impulses, the portions of the couplings for said local circuits in said antenna circuit being arranged in series, and a third local circuit coupled to said two first mentioned local circuits independently of said antenna circuit, all three of said local circuits containing means for varying the natural period thereof.
- 100 11. In a radio signaling receiving station the combination with an antenna circuit, including inductance and capacity, of two local circuits coupled to said antenna circuit each tuned to a frequency differing from that of the antenna circuit and differing with respect to each other, a third local circuit separate from said antenna circuit containing variable tuning means and a receiving device, said third local circuit being tuned to a frequency different from that of either of the two first-named local circuits, and means separate from said antenna circuit for associating said third local circuit with the two first-named local circuits.
- 115 12. In a radio signaling receiving station the combination with an antenna circuit, including inductance and capacity of two local circuits coupled to said antenna circuit, the portions of the couplings for said local cir-
- 95 105 110 115 120 125 130

cuits in said antenna circuit being in series, each of said local circuits including wave responsive devices and being tuned to a frequency differing from that of the antenna circuit and differing with respect to each other, a third local circuit separate from said antenna circuit containing variable tuning means and a receiving device, and means separate from said antenna circuit for associating said third local circuit with the two first-named local circuits.

13. In a radio signaling receiving station the combination with an antenna circuit, including inductance and capacity of two local circuits coupled to said antenna circuit, the portions of the couplings for said local circuits in said antenna circuit being in series, each of said local circuits being tuned to a frequency differing from that of the antenna circuit and differing with respect to each other, a third local circuit separate from said antenna circuit and containing variable tuning means and a receiving device, and

means separate from said antenna circuit for associating said third local circuit with the two first-named local circuits.

14. In a radio signaling receiving station the combination with an antenna circuit, including inductance and capacity of two local circuits coupled to said antenna circuit, each tuned to a frequency differing from that of the antenna circuit, and differing with respect to each other, a third local circuit separate from said antenna circuit containing variable tuning means and a receiving device, said third local circuit being tuned to a frequency lower than that of the two other local circuits, and means separate from said antenna circuit for associating said third local circuit with the two first-named local circuits.

ELMER E. BUTCHER.
